UNITED STATES PATENT OFFICE.

DURBIN RICHARDSON AND CHARLES N. JACOBY, OF ROCHESTER, NEW YORK,
ASSIGNORS TO RICHARDSON CORPORATION, OF ROCHESTER, NEW YORK, A
CORPORATION OF NEW YORK.

DESIGN FOR A BEVERAGE-DISPENSING VEHICLE.

● 58,828.

Specification for Design.

Patented Aug. 30, 1921.

Application filed May 2, 1921. Serial No. 466,229. Term of patent 14 years.

To all whom it may concern:

Be it known that we, DURBIN RICHARDSON and CHARLES N. JACOBY, of Rochester, in the county of Monroe and State of New York, have invented a new, original, and ornamental Design for a Beverage-Dispensing Vehicle, of which the following is a specification, reference being had to the accompanying drawings, forming a part thereof.

Figure 1 is a side elevation, with the side

doors of the vehicle open and showing the parts in position for dispensing beverages, and

Fig. 2 is a rear perspective view of the same.

We claim:

The ornamental design for a beverage dispensing vehicle, as shown.

DURBIN RICHARDSON.
CHARLES N. JACOBY.
